UNITED STATES PATENT OFFICE

2,618,951

YARN CHANGER WITH CLAMPING AND CUTTING MEANS

William J. Longtin, Philadelphia, Pa., assignor
to H. Brinton Co., Frankford, Philadelphia, Pa.,
a corporation of Pennsylvania

Application September 28, 1950, Serial No. 187,188

4 Claims. (Cl. 66—140)

1

My invention relates to cutting and clamping means intended primarily for use in a circular knitting machine with a revolving cylinder or a revolving cam ring, in connection with yarn changing means whereby any one of a group of yarns may be put into action under control of pattern mechanism, and it is an object of the invention to provide means for cutting off an idled yarn more certainly and effectively than has been possible with previously known means.

Another object is to provide improved means for holding the ends of all idle yarns.

Another object is to provide improved yarn cutting and clamping means that shall be simpler in construction than previously known devices for the same purpose, and which shall consequently be less expensive to produce, more durable, and less liable to get out of order.

Referring now to the annexed drawings, which are made a part of this application and in which similar reference characters indicate similar parts:

Fig. 1 is a perspective of my improved device,

Fig. 2, a partial side elevation of the same, with parts in open position to receive a newly idled yarn,

Fig. 3, a similar view, with said parts closed,

Fig. 4, a horizontal section on line 4—4 of Fig. 2,

Fig. 5, a section on line 5—5 of Fig. 1, and

Fig. 6, an exploded view of working parts shown in other views.

In the drawings, reference character 10 indicates a block carrying the yarn fingers 11 which are located side by side for pivotal movement to place yarns in idle or non-feeding position or in position to be fed to independent needles at the knitting point. The springs 12 that bias them toward idle position, the mouth piece 13 and other parts, including the means for putting the yarn fingers into feeding position, are or may be such as disclosed in the patent to Aaronson, 1,883,320, October 18, 1932. A lock 14 is secured to one side of the block 10 by means of screws 15 and a plate 17 is affixed to the outer face of block 14 by means of screws 18', said plate 17 having holes at 16 that afford access to the heads of screws 15.

In a longitudinal groove in the outer face of the block there is mounted a spring plate 18 which has a protruding hook 19 at its outer end for engaging idled yarns and guiding them to a gap in rear of said hook and so to the clamping and cutting devices. This plate has a hole at 20 that is engaged by a screw 21 for holding it against endwise movement.

2

A slide 22 is also located in said groove, said slide being movable approximately radially of the machine so as to intercept a yarn extending from an idle finger to the needle circle. Said slide has a slot at 23 to permit the slide to move endwise. A spiral spring 24 is attached at one end to a pin 25 on slide 22 and at the other end to a pin 26 on plate 17 for holding the parts in the position of Fig. 2. An outer spring plate 27 presses the slide 22 against the plate 18 due to the pressure of plate 17 against plate 27, and the plate 27 is held against endwise movement by engagement screw 21 in its hole 28. The plate 17 is cut away at its lower front corner at 29 (Fig. 2) to leave space for pin 25 to reciprocate.

The slide 22 has a shear edge at 30' at the rear of a depending lug 30 which coacts with a shear edge at 31 on plate 27 to sever any yarns that may come between said edges, and at the same time the ends of any idle yarns are clamped between the contiguous faces of plate 18 and slide 22 and held there until the finger controlling such a yarn is moved into feeding position and the slide 22 is advanced by pattern-actuated mechanism (which may be substantially similar to what is shown in the Aaronson patent above referred to). A plate 22a similar to plate 12 of the patent acts on the rear end of the slide 22 to move it toward the axis of the machine against the tension of spring 24. That part of the pattern-actuated mechanism which thus actuates the slide comprises a plate 22a with a cam edge 22b that acts to advance the slide when the plate 22a is elevated by well-known pattern mechanism and the cam edge is followed by a working face 22c that is long enough to hold the slide in the advanced position of Fig. 3 until the newly idled yarn (or yarns) has entered the gap at the forward or left hand end of the parts 18, 22 and 21, after which the end of slide 22 rides off the working face 22c of its pattern mechanism member and the spring 24 snaps the slide back to its shear closing position, so that any yarns that are in the gap are cut off by the snap shear action which is a very important feature of the invention in producing certainty of cutting off. The idle yarns are clamped at their free ends between the contiguous faces of slide 22 and spring plate 18.

It will be obvious to those skilled in the art that numerous changes may be made in the devices herein disclosed, all without departing from the spirit of the invention; and therefore I do not limit myself to what is shown in the drawings and described in the specification, but only as indicated in the appended claims.

I claim:

1. In a circular knitting machine having a set of pivoted yarn fingers located side by side for selective movement from idle position to yarn feeding position, the combination of a slide adjacent the yarn fingers, said slide having a depending lug at its inner end next to the needle circle said lug having a shear edge, fixed spring plates mounted at opposite sides of said slide and bearing against the slide at their inner ends, one of said plates having a hook providing a gap located to receive an idled yarn at a point between the needle circle and the corresponding yarn finger, said plate having a face coating with an adjacent face on the slide to clamp the ends of idled 15 yarns, and a shear edge on the other one of said fixed plates positioned to coact with the first-named shear edge for severing idled yarns.
2. A device as in claim 1, including pattern actuated means for advancing the slide, and 20 spring means for returning the slide.
3. A device as in claim 1, including a pattern-actuated cam for advancing the slide, said cam being shaped to advance the slide gradually and to release it sharply, and spring means acting on the slide to retract it with a snap action upon 25 its release.
4. In a circular knitting machine having a set

of yarn fingers located side by side for selective movement from idle position to yarn feeding position, the combination of a slide having a depending lug at its inner end next to the needle circle, fixed plates bearing against opposite faces of the slide, a depending lug on one of the fixed plates, said lug having a shear edge coacting with the first-named shear edge for severing idled yarns, and a hook on the other one of said plates 10 providing a gap located to receive an idled yarn between its yarn finger and the needle circle, said other plate having a face coating with an adjacent face on the slide to clamp the severed end of an idled yarn.
